(57) **CLAIM**

The ornamental design for a floating splice extrusion, as shown and described.

DESCRIPTION

This application contains subject matter related to the following co-pending U.S. design patent application:

Application Ser. No. 29/580,883, filed Oct. 13, 2016 and entitled "Microrail Attached Base Extrusion".

FIG. 1 is a perspective view of a floating splice extrusion according to the design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

(Continued)

The broken lines show portions of the floating splice extrusion that form no part of the claimed design.
